UNITED STATES PATENT OFFICE.

JOSEPH A. MUMFORD, OF ROSLYN, NEW YORK, AND DAVID W. ROBB, OF AMHERST, NOVA SCOTIA, CANADA.

STEAM-GENERATOR.

No. 845,885.

Specification of Letters Patent.

Patented March 5, 1907.

Application filed May 22, 1906. Serial No. 318,194.

To all whom it may concern:

Be it known that we, JOSEPH A. MUMFORD, of Roslyn, in the county of Nassau and State of New York, and DAVID W. ROBB, of Amherst, Province of Nova Scotia, Dominion of Canada, both subjects of the King of Great Britain, have invented certain new and useful Improvements in Steam-Generators; and we do hereby declare the following to be a full, clear, and exact description of the same, reference being had to the accompanying drawings, forming part of this specification, and to the figures and letters of reference marked thereon.

15 This invention relates to improvements in steam generators or boilers of the water-tube type, and while features of the invention are applicable generally to boilers of this type the invention is shown in connection with a 20 water-tube boiler wherein water-tubes are arranged in an inclined position in the furnace-setting and at their ends open into or communicate with suitable drums and headers, as is well understood in this art.

25 The invention consists in certain novel details of construction and combinations and arrangements of parts, whereby increased efficiency is secured, the shells of the drums and headers strengthened, and distortion 30 and racking of the parts due to expansion and contraction to a large extent overcome.

Referring to the accompanying drawings, Figure 1 is a vertical section through a steam-generator and its setting embodying the 35 present improvements, certain parts being shown in elevation. Fig. 2 is a detail section through a portion of the front drum and its depending header for the lower bank of tubes. Fig. 3 is a detail front elevation of a 40 portion of the front drum and header, portions of the front shell of each being broken away to show the internal construction. Fig. 4 is a view corresponding to Fig. 1, but with a slightly-modified construction of the 45 drums.

In said drawings the letter A indicates the boiler-setting, which, as usual, is made in the form of a combustion-chamber, within which the steam-generator is located and supported, 50 the furnace-grate and bridge-wall B and C,

respectively, being located in the lower portion of the setting and near the forward end of the same. These parts may all be of any usual or preferred type and provided with the usual clean-out and fuel and ash-pit doors. Two drums D and E are located in the upper portion of and at front and rear, respectively, of the setting, the center line of one of said drums, preferably that at the back of the setting and lettered E, being somewhat above the center of the forward drum, (lettered D.) Thus the drum E becomes the steam-drum, from which the steam may be withdrawn through a suitable outlet, such as c. The drums E and D are connected by two sets of pipes or tubes F and F', the former being preferably located above the water-level to serve as steam-passages and as steam-superheaters, while the latter are located below the water-level and serve as a part of the water-circulating system of the generator.

At the rear of the setting A and below the drum E are located two additional drums G and H, preferably of similar formation and arranged parallel to and one above the other. The upper one of these drums, that lettered G, is connected with the forward drum D by a bank of tubes I, and the lower one, H, is connected with a header L by a bank of tubes K, the said header L being in turn connected at its upper edge with the lower portion of the drum D, so as to form an integral extension thereof, it being understood that suitable communicating openings are formed in the shell of the drum D for opening communication between the header and drum. The banks of tubes I and K are inclined downwardly from the front of the generator at such an angle as to secure the best circulation and action of the heated products of combustion thereon. In order to give a prolonged action by said products on the tubes, suitably-inclined partitions k and i are located above the respective banks of tubes K and I, the former partition k being extended from the header L diagonally downward toward the rear of the generator and the latter partition i being extended from the drum G in an upwardly-inclined direction toward the

front of the generator, whereby the products of combustion are first caused to traverse practically the full length of the lower bank of tubes and then traverse practically the full length of the upper bank of tubes and finally to pass through the upper portion of the setting around the tubes F and F' and beneath the drum E to the smoke-outlet M at the rear of the setting.

- 10 The drums E, G, and H are connected by substantially vertical tubes, preferably arranged in independent sets N and O. Thus each of the banks of tubes I and K, together with its drum G or H, constitutes part of a 15 separate circulating system, and each set of tubes, with its drum G or H, is free to expand and contract independently of the other set without causing distortion or racking of the tubes or generator connections.
- 20 The drums G and H constitute mud-drums for the collection of sediment, and they are therefore each provided with blow-off pipes P.

While the drums D, G, and H may be cylindrical drums, as shown in Fig. 4, and the ends of the tubes connecting therewith bent to enter said drums radially, in the preferred construction the said drums are provided with flat faces in which the tube-openings 25 are formed, such faces being indicated in Fig. 1 by the letters d, g, and h, respectively. With this construction it is highly desirable that the flat faces shall be braced and strengthened to approximate in strength the 30 cylindrical portions of the drums without the necessity of employing heavier metal in the flattened portions. To accomplish this successfully and at the same time permit of the employment of the maximum number of 35 tubes in staggered relation to each other, so that the products of combustion will be forced to follow a tortuous path in passing through between the tubes, we now make use of sinuous stays which are riveted to the 40 inner faces of the flattened portions of the drums.

The sinuous formation of the stays permits them to pass between the ends of the tubes or openings for the ends of the tubes without 45 coming into such proximity thereto as to interfere either with the heading of the tubes or the cleaning of the same after the generator is in use. In the preferred construction these sinuous stays, as well illustrated in Figs. 50 1 and 3, are formed of flanged metal. Thus the sinuous body of the stays is indicated by the letter Q, and the flanges on said stays are indicated by the letter q and q'. In order to provide for the employment of wide flanges 55 60 which may be riveted to the face of the drum and at the same time avoid interference with the ends of the tubes or tube-openings, the flanges are formed on one side or the other of

the body of the setting in accordance with the space to be found between the tube-openings. Thus in said Fig. 3 it will be noted that the flange q is on one side of the body of the stay, where sufficient room is found for the rivets, and the flange q', which is intermediate the two portions of the flange q, is 65 located on the opposite side of the body of the stay, where sufficient room is found for the location of its rivets, while opposite the flange q' and between the sections of the flange q a space is left for one of the tubes. 70

From the foregoing it will be seen that the staggered arrangement of tubes is used in connection with a staggered or sectional arrangement of the flanges on the stays, whereby each will perform its functions without 80 interfering with the other and at the same time the maximum strength in the drum may be secured.

The header L, which depends from the drum D, is preferably formed of plate metal 85 bent into substantially U form in cross-section, but with parallel side walls, and the bank of tubes K enters this header in the inner side wall. The outer face or wall of the header is provided with the usual hand-holes l, and in order to brace and strengthen the header to correspond to the strength of the other portions of the generator the two side walls are connected together by sinuous stays R, which correspond in construction very closely to the stays Q herein-before described—that is to say, the body of each stay is made sinuous to pass the staggered ends of the tubes and the opposite edges of the body of the stay are flanged, as shown clearly in Figs. 2 and 3, and united rigidly to the two opposite walls of the header by rivets. The flanges on the stays R are divided into sections, which extend alternately in opposite directions, as shown at r and r', the staggered arrangement of the flanges corresponding to the staggered arrangement of the tubes. Thus each flange-section projects into the space between tubes, which are in the same vertical plane, where ample space 100 is found for the attaching-rivets without undue weakening of the shell, and without in any wise interfering with or obstructing the tube-openings.

In the preferred construction the stays R, 105 in addition to being secured to the walls of the header, are also secured to the shell of the drum D. Thus, as shown in said Figs. 2 and 3, the upper end of each stay is flanged and united to the said shell by rivets, as indicated at S.

The lower end of each stay is preferably 110 somewhat removed from the bottom of the header, thereby providing a small circulating-space under each stay, and at the same 115 time this space does not permit of the circu-

lation of a volume of water equal to the capacity of the tubes between the stays or between the endhead and first stay. While a circulation will be maintained under all conditions in all of the tubes, nevertheless the circulation will be augmented in those tubes subject to the greatest heating effect of the products of combustion, and consequently not only will the generation of steam be increased, but the tubes will be prevented from being burned out where subjected to the direct action of the products of combustion.

While all of the drums may be provided with hand-holes or manholes, as is usual in boilers of this class, it is preferred to locate the manhole D' in the drum D opposite to the tube-openings, thus providing for the ready cleaning of the tubes.

20 In the preferred construction shown in the drawings the entire generator, including its drums and header, is located within the walls of the setting, the only portions exposed in the exterior being the manholes D' of the front drum; but in the said setting and opposite the hand-holes l of the header there is provided a door or cover-plate T for giving access to the said header, whereby repairs and cleaning may be effected without entering or disturbing the setting.

Having thus described our invention, what we claim as new, and desire to secure by Letters Patent, is—

1. In a steam-generator, the combination with the two independent banks of inclined water-tubes located one above the other, a drum at the upper forward ends of said banks of tubes and with which they both communicate and separate drums at the lower rear ends of said tubes, each bank being in communication with its own separate drum whereby each bank is free to expand and contract independently of the other, of an upper rear drum located approximately over the said lower rear drums, independent circulating-tubes connecting said lower rear drums and the upper drum whereby they may expand and contract independently, and circulating-tubes connecting the rear and forward upper drums said last-mentioned tubes being independent of both the banks of tubes and vertically-arranged circulating-tubes and the whole arrangement being such that longitudinal expansion and contraction of any set of tubes is not resisted by the longitudinal resistance of any other set of tubes.

2. In a steam-generator, the combination with a bank of tubes, the several tubes being staggered with relation to each other and a water-chamber into which said tubes enter, of a sinuous stay secured to the inner face of said water-chamber between the entrance-

openings of the tubes; substantially as described.

3. In a steam-generator, the combination with a bank of tubes, the several tubes of said bank being staggered with relation to each other, of a water-chamber into which the ends of said tubes enter and a flanged sinuous stay secured to the inner face of said chamber between the entrance-openings of the tubes; substantially as described.

4. In a steam-generator, a bank of tubes wherein the several tubes are staggered with relation to each other, of a water-chamber into which the ends of said tubes enter and a sinuous stay secured to the inner face of said chamber between the entrance-openings of the tubes and oppositely-projecting sectional flanges on said stay for securing the same in position between the tube-openings; substantially as described.

5. In a steam-generator, a bank of tubes wherein the tubes are staggered with relation to each other, a water-chamber into which the ends of said tubes enter and a sinuous stay passing between the entrance ends of said tubes and having sectional flanges, said flange-sections being staggered in accordance with the arrangement of the tubes, for securing the stay in position between the tube-openings; substantially as described.

6. In a steam-generator, the combination with a bank of tubes, wherein the tubes are staggered with relation to each other, of a drum having a flat face into which the ends of said tubes are entered and a separate sinuous stay secured to the inner side of said flat face between the entrance-openings of the tubes; substantially as described.

7. In a steam-generator, the combination with a bank of tubes wherein the tubes are staggered with relation to each other, of a drum having a flat face into which the ends of said tubes are entered and a sinuous stay secured in position against the inner side of said flat face, said stay having oppositely-projecting sectional flanges for securing it in position; substantially as described.

8. In a steam-generator, the combination with a bank of tubes wherein the tubes are staggered with relation to each other, of a flat-faced header into one face of which said tubes are entered hand-holes in the other face of said header opposite the tube-entrances and separate sinuous stays uniting the flat faces of the header intermediate the tubes; substantially as described.

9. In a steam-generator, the combination with a bank of tubes wherein the tubes are staggered with relation to each other, of a header having flat faces into one of which the ends of said tubes are entered, hand-holes in the other face of said header opposite the tube-entrances and flanged sinuous stays

uniting the flat faces of said header intermediate the tube-entrances and hand-holes; substantially as described.

10. In a steam-generator, the combination with a bank of tubes wherein the tubes are staggered with relation to each other, of a flat-faced header into one face of which the ends of said tubes are entered, hand-holes in the other of said faces opposite the tube-entrances and sinuous stays having oppositely-projecting sectional flanges united to the op-

posite faces of the header intermediate the hand-holes and tube-entrances; substantially as described.
